US00D617295S

(12) **United States Design Patent**
Lee et al.

(10) **Patent No.:** US D617,295 S
(45) **Date of Patent:** ** *Jun. 8, 2010

(54) **PORTABLE TELEPHONE**

(75) Inventors: **Ki-Eon Lee**, Kyunggi-do (KR);
Yoon-Young Cho, Seoul (KR);
Chang-Hwan Hwang, Kyunggi-do (KR)

(73) Assignee: **Samsung Electronics Co., Ltd.**,
Kyunggi-do (KR)

(*) Notice: This patent is subject to a terminal disclaimer.

(**) Term: **14 Years**

(21) Appl. No.: **29/312,004**

(22) Filed: **Sep. 24, 2008**

(51) **LOC (9) Cl.** **14-03**

(52) **U.S. Cl.** ..... **D14/138 AA**

(58) **Field of Classification Search** ..... D14/138 AA,
D14/138 R, 147, 341, 346, 137; 455/575.1,
455/90.3, 556.1; 379/433.01, 433.04

(57) **CLAIM**

The ornamental design for a portable telephone, as shown and described.

DESCRIPTION

FIG. 1 is a top front perspective view of a portable telephone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
